UNITED STATES PATENT OFFICE.

FRANK E. WILLIAMSON, OF NOBLESVILLE, INDIANA.

PERMUTATION LOCK.

Application filed August 16, 1923. Serial No. 657,736.

To all whom it may concern:

Be it known that I, FRANK E. WILLIAMSON, a citizen of the United States, residing at Noblesville, in the county of Hamilton and State of Indiana, have invented certain new and useful Improvements in Permutation Locks, of which the following is a specification.

My invention relates to permutation locks and has for its object to produce a lock of this kind that is comparatively simple in construction, the parts of which are not liable to get out of order, which is reliable in use, and which cannot be readily operated by one unfamiliar with the combination of the particular lock to be manipulated, all of which will be set out in the accompanying specification.

Referring to the drawings—

Figure 1 is a plan view of a lock embodying my improvements, the top plate of the casing being removed; the positions of the parts when the bolt is withdrawn and unlocked being represented in full lines, and when the bolt is thrown and locked by dotted lines.

Fig. 2 is a side elevation of the lock, one of the side plates of the casing being removed.

Fig. 3 is a transverse sectional view on the line III—III of Fig. 2.

Fig. 4 is a view similar to Fig. 1, except that the parts of the lock are indicated in the positions they occupy after the selective finger bars have been manipulated and the permutation bar moved to free the locking bolt.

Fig. 5 is a detail view in plan showing a portion of a permutation bar with contact projections of a rigid nature.

Referring to the drawings, 2 designates the casing that encloses the working parts of the lock. Next to one wall of the casing, which I herein term the bottom wall, is supported the sliding bolt 3, one end of which extends through an end plate of the casing and is provided with a finger piece 4. The opposite end of the locking bolt is adapted to be projected through the end wall of the casing, when the bolt is thrown, or to be withdrawn entirely within the casing, accordingly as the bolt is manipulated, and as will be hereinafter described. Springs 5 act upon the bolt and tend to move it to inactive position, that is, with its locking end within the casing, as represented in full

lines in Fig. 1. A recess 10 is formed in one edge of the locking bolt.

A key 9 crosses the locking bolt, being arranged transversely within the casing 2 60 and preferably just above the bolt. One of its ends extends through a side wall of the casing and is provided with a knob or manipulating piece 9'. In the underside of the shaft of the key 9 is formed a recess 20 65 in which lies the locking bolt, this recess being of a length substantially equal to the width of the bolt. A spring 7 acts upon the key and tends to move it to its inner or locking position, represented by dotted 70 lines in Fig. 1, which position is taken when the bolt 3 is moved toward the right, Fig. 1, by pushing inward upon the finger piece 4. This brings the notch or recess 10 in the edge of the bolt opposite to the shoulder 75 21 of the key shaft, which then moves inward under the action of the spring 7, locking the bolt. The inner end of the key lies within a housing 11 secured to the inner face of the rear side wall of the casing 2. 80

14 designates a permutation bar which is preferably located above and parallel with the bolt, it being supported at its opposite ends in housings 12, 12' secured to the end walls of the casing, in which 85 housings are also supported the ends of the locking bolt 3. The permutation bar lies entirely within the casing and is of such length that it may be freely moved longitudinally to a limited extent therein. It 90 is acted upon by a spring 6 that normally moves it to its extreme limit of movement toward the left as is seen in Figs. 1 and 2.

The permutation bar carries a set of pins or projections 16 which preferably extend 95 from the upper face thereof. It is moved by a set of key bars 17, which I will presently describe, and is adapted to operate a latch 27 that serves to hold the key in locking position, that is, in engagement with the notch 10 in the locking bolt, as has been described. The latch 27 is pivoted at 15 and is formed with a toe 27' that is adapted to pass through an opening in the housing 11 and enter the recess 13 in the key 100 shaft 9 when the later is moved inwardly or into locking position. A spring 8 acts upon the latch 27 and forces its toe 27' into the recess 13 when the key and other parts 105 come to locking position.

30 indicates a contact pin carried by the permutation bar 14 and arranged to act

upon the heel of the latch 27 and move it, against the action of the spring 8, to release the key whenever the permutation bar is moved to the limit of its travel toward the right.

The key bars 17 which have been referred to are supported in the opposite side walls of the casing, in position preferably just above the permutation bar 14. They are free to be moved longitudinally in their supports and each carries a contact pin 18 adapted to act upon one of the projections 16 carried by the permutation bar. The contact pins 18 may carry rollers 28 to lessen friction and tend to the easy working of the apparatus when the key bars are moved to engage with and operate the permutation bar. The contact projections 16 carried by the permutation bar might be rigid or stiff members projecting from the upper face of the permutation bar and formed with inclined faces with which engage the contact pins 18 of the finger bars as represented in Fig. 5. I prefer, however, that the contacts 16 should be pivotally supported on the permutation bar, as represented at 31 in Figs. 1 and 4. A spring 32 acts upon each pivoted contact piece 16 and maintains it in normal working position with its inclined face 33 in position to be acted upon by a contact pin 18 of a key bar. The spring 32 acts to hold the heel of the pivoted contact piece 16 against a stop 34 the arrangement shown rendering the contact 16 rigid or stiff when the contact pin 18 comes into working engagement with its inclined face 33, but yielding when the said contact pin comes into engagement with its opposite or rear face, allowing the pin 18 to freely pass.

The key bars 17 preferably extend outwardly beyond both side walls of the casing where they are provided at their opposite ends with finger pieces 22. They are free to be moved in either direction accordingly as the finger piece at one or the other end is pressed. Some of the contact pins 18 which they carry may be located so as to occupy positions to one side of the permutation bar, some to the other side, and others to be over the center of the permutation bar, when the key bars all occupy a mid or central position, as represented in Fig. 1; but from the outside of the casing it is impossible to tell the location of these contact pins, and their different relative positions determine the manner of operating the lock. It follows that one unfamiliar with the arrangement of these contacts 18 in a particular lock will not know whether a particular finger bar is to be moved toward the right or toward the left in order to operate the permutation bar, nor would he know the sequence in which the finger keys are to be manipulated in order to effect movements of the permutation bar. The key bars are preferably not

only longitudinally movable as has been described, but are rotative so that the contacts 18 which they carry may be turned out of position so as not to operate upon the contacts 16 of the permutation bar, thus making it necessary that the several key bars shall be first rotated to proper positions before longitudinal movements of them can be effective in imparting any movement to the permutation bar. I therefore prefer to form the key bars non-circular in cross section and to so support them that when they are moved longitudinally to operate the permutation bar they are supported so as to be non-rotatable. I prefer to construct the key bars as shown, that is to say, the main portion of each bar is hexagonal in cross section, as represented at 25, and there is a short portion between the hexagonal part and one of the finger pieces 22 that is cylindrical, as represented at 23. The supports for the key bars are formed in or carried by the side walls of the casing, and shaped to fit the hexagonal parts of the bars fairly closely, thus serving to prevent the bars from being turned so long as the non-circular portions thereof are in such supporting parts. If, however, a bar be slid endwise until the circular portion 23 thereof occupies the bearing or support it may then be rotated. The contact pin or projection 18 carried by a key bar extends out radially from one of the flat faces of the hexagonal part thereof, and it will be understood that the bar must be turned to the proper position in order that the contact piece 16 carried by the permutation bar with which said projection is to operate. In order to assist one in using the lock to quickly determine the proper angular position to be assumed by a key bar in order that it may be operative, a finger piece 22 thereof may carry a designating mark or projection, such as indicated at 19, having an angular relation to the projection 18 known only to the user. By this means one familiar with the lock may first shift a key bar 17 longitudinally until its cylindrical portion 23 occupies the bearing carried by the side wall of the casing, and then angularly adjust it until the projection 18 comes to position to engage with the co-operating contact of the permutation bar, after which the key bar will be slid until its hexagonal or non-circular portion is seated in the bearing, resulting in holding the bar in position to act upon and operate the permutation bar when it is properly moved.

24 designates a spring adapted to bear upon the several key bars 17. It preferably consists of a ribbon of spring steel extending from end to end of the casing and supported so that it bears with proper force upon the hexagonal portions of the bar 17. Its function is to prevent the too free move-

ment longitudinally of these bars in their supports.

It will be seen by reference to Figs. 1 and 2 that the projections 16 carried by the permutation bar are arranged irregularly, so that at any one position of the permutation bar but a single one of said projections is in the path of movement of a contact pin 18 carried by a key bar. In the arrangement shown in the drawings, when the parts are in normal position, that is, when the permutation bar is moved to its extreme position to the left, the first contact 16 from the left is the only one in the path of movement of a contact pin 18, all of the other contacts 16 being out of line with their respective contact and operating pins 18. The result is that a longitudinal movement of any key bar except the proper one,—in this instance the first key bar—has no effect whatever on the permutation bar, and, with the contact pin 18 located as represented, only a movement of said first key bar in the direction toward the person viewing Fig. 1, will be effective to move the permutation bar.

I will now set forth the manner of using a lock such as I have described and illustrated, it being assumed that the parts are in their inactive positions, as represented in full lines in Fig. 1. The part to which the lock is secured being moved so that the end of the locking bolt 3 is opposite the keeper with which it is to engage, the one using the lock presses inwardly upon the finger piece 4 of the bolt, pushing it to the right and into locking position. This movement brings the recess 10 in the edge of the bolt opposite the key 9 which, under the action of the spring 7, is moved forward or inwardly, the shouldered portion 21 thereof entering the recess 10 and locking the bolt 3. At the instant the key comes to its innermost position the opening 13 therein is opposite the toe of the latch 27 which, under the influence of the spring 8, enters said recess and locks the key. The parts of the lock now occupy the positions indicated by dotted lines in Fig. 1, where they are locked or held until freed by the movement of the permutation bar, which takes place only upon the proper manipulation of the key bars 17. To unlock the bolt 3 the following manipulations have to be performed. In the first place, the several key bars must be angularly adjusted to bring their contact pins 18 into proper positions to engage with the contacts 16 with which they severally co-operate. The first key bar, from the left, is then longitudinally moved so that the contact pin 18 thereof stands on the side of the contact piece 16, facing its inclined face 33, if it does not already occupy that position, and is then moved downward, or in a direction toward the person viewing Fig. 1, causing the pin 18 to engage with the in-

clined face 33 of the contact 16. This causes the permutation bar to be moved forward or toward the right one step, where it is held by the pin 18 remaining in front of the contact 16. The second key bar to be manipulated, the third bar of the series, is now operated. The location of its contact pin 18 is such that the bar must be moved in a direction opposite that of the first bar, in order to properly engage with its co-operating contact 16, to cause a second advance movement of the permutation bar. The latter is held in its advance movement by the pin 16 of the said third bar stopping in front of contact 16 in position to prevent reverse movement of the permutation bar. The third key bar to be manipulated, the second one of the series, has its contact pin 18 located at the center of the bar 17, and hence in order to give to the permutation bar its third forward movement this key bar must first be moved to clear the contact piece 16, this being permitted because the contact piece is pivoted, and then the bar moved in the opposite direction to cause such engagement with the contact piece 16 as to advance the permutation bar a third step. The last movement is performed by manipulating the fourth key of the set, and its operation will be apparent from the drawings. As the final movement of the permutation bar takes place the contact piece 30 carried by the permutation bar engages with the heel of the latch 27, rocking it upon its pivot, and releasing the key. This may be then pulled outward, by engaging with the finger piece 9' to release the locking bolt which is thereupon moved by the springs 5 and withdrawn from its keeper.

The parts are now in the positions indicated in Fig. 4, being held in such positions by reason of the fact that the contact pin 18 of the last key bar to be manipulated, the fourth of the series, is standing behind the contact 16, or in its path of movement.

If now the fourth key bar only be moved longitudinally the permutation bar will be released and be moved back by its spring 6, but it will move only one step, because it will be caught and arrested by the contact pin 18 of the second key bar. Should the locking bolt now be moved forward into locking position the parts will assume their locking relationship as indicated by dotted lines, Fig. 1, but to release the bolt it is only necessary to move the fourth or last-to-be-operated key bar.

It is apparent that my invention is not limited to the specific form of lock which I have illustrated and herein described. For instance, the number of key bars might be increased or diminished, an arrangement of contact parts 16 and 18 different from those shown could be adopted, locking means for holding the key 9 different from the latch

27 might be used, and other changes made, within the scope of my invention as defined by the claims hereof, such as would readily suggest themselves to those skilled in the 5 art.

What I claim is:—

1. In a permutation lock, the combination 10 with a casing and a locking bolt supported therein, of a key controlling the movements of the bolt, a permutation member movable independently of the key and carrying contacts, arranged to control the working relationship between the key and the bolt, and selective devices for engaging 15 with the said contacts of the permutation member in determined sequential order to effect movement thereof to the position to permit the key to operate.

2. In a permutation lock, the combination 20 with a casing and a sliding bolt supported therein, of a key movable within the casing arranged to engage directly with and to control the operation of the bolt, a permutation member movable independently 25 of the key and arranged to control its operation, and manually controlled selective devices arranged when operated in proper sequential order, to engage with and move the permutation member to position to permit 30 the key to be operated to release the bolt.

3. In a permutation lock, the combination 35 with a casing and a sliding bolt supported therein, of means for moving the bolt, a longitudinally movable key supported within the casing, arranged to be brought into engagement with the bolt to lock it, a permutation member arranged to free the bolt from the key when it is moved to a predetermined position, and selective devices 40 for moving the permutation member to position to free the bolt, when manipulated in proper sequential order.

4. In a permutation lock, the combination 45 with a casing and a sliding bolt supported therein, of means for throwing the bolt, a key for locking the bolt, a sliding permutation bar arranged to control the operation of the key, a series of projections having inclined faces carried by the permutation bar, and selective manually-operated sliding bars carrying contact pieces, arranged to engage with the inclined faces of the projections carried by the permutation bar, when operated in proper sequential order.

5. In a permutation lock, the combination 50 stated in claim 4 in which the contact projections carried by the permutation bar are stiff when engaged from one direction and yielding when engaged from the opposite direction.

6. In a permutation lock, the combination 55 with a casing and a sliding bolt supported therein, of a key comprising a shaft supported in the casing so it may move longi-

tudinally to bring it either into position to permit the bolt to be thrown or to a position where it will prevent such movement of the bolt, a longitudinally movable permutation bar arranged to control the movements of the key, and manually operated selective devices for moving the permutation member, when manipulated in the proper sequential order.

7. In a permutation lock, the combination 70 with a casing, a bolt supported therein, and a key for locking the bolt, of a permutation bar arranged to release the bolt when the bar has been moved to a predetermined position, contact pieces carried by the bar, and a series of sliding selective bars arranged transversely with reference to the permutation bar, the opposite ends of the selective bars being exposed and they being free to move in either direction, accordingly as one end or the other is pressed, pins carried by the selective bars arranged to engage with the projections on the permutation bar to move it when the selective bars are moved in proper sequential order and in 80 the proper direction, certain of the pins carried by the selective bars being to one side of the permutation bar and certain to the other side.

8. In a permutation lock, the combination 90 of a casing, a locking bolt supported therein, means for moving the bolt, a key supported within the casing and movable longitudinally either to position to permit 100 operation of the bolt or to position to prevent operation of the bolt, a longitudinally movable permutation bar arranged above the bolt, a set of projections carried by the permutation bar, a set of longitudinally movable selective bars arranged transversely with 105 reference to the permutation bar, the ends of the selective bars extending through the walls of the casing and being exposed so they may be moved in either direction by 110 pressing on one end or the other of the bars, and pins carried by the selective bars arranged to act upon the projections carried by the permutation bar when the selective bars are operated in the proper sequential order, certain of the pins being located on 115 one side of the projections and certain on the other side, the projections of the permutation bar having inclined faces with which the said pins are adapted to engage.

9. In a permutation lock, the combination 120 with a sliding locking bolt, a manually controlled key device by which the bolt is locked, a permutation member, manually controlled selective devices arranged to operate the permutation member, restraining means for preventing the key device from being operated, and means carried by the permutation member for moving the said restraining means as it comes to its final 125 position.

10. The combination stated in claim 9 when the restraining means are in the form of a spring actuated latch.

11. The combination stated in claim 9 having the permutation member and the key device arranged so as to cross each other at substantially right angles, but each being located in different horizontal planes.

12. In a permutation lock, the combination of a sliding bolt in the edge of which is formed a recess, a key device for controlling the movements of the bolt supported so as to be movable across the bolt and carrying a part adapted to enter the recess in the edge thereof to lock the bolt or to be withdrawn from such recess to free the bolt, means for restraining the key device in position to engage with and hold the bolt, a permutation bar, manually operated means for operating the permutation bar, and means controlled by the permutation bar for removing the said restraining means and permitting the key device to free the bolt.

13. In a permutation lock, the combination of a sliding bolt in the edge of which is formed a recess, a key device for controlling the movements of the bolt supported so as to cross the bolt and recessed on one side so that the bolt is movable in said recess, the key device being formed with a shoulder adapted to enter the recess in the edge of the bolt to lock the same or to be

withdrawn from said recess to free the bolt, a pivoted latch arranged to engage with the key device and restrain it when in locking engagement with the bolt, a permutation bar, manually controlled means for operating the permutation bar, and a contact part carried by the permutation bar arranged to act upon the said latch and release the key device when the permutation bar is moved to a determined position.

14. In a permutation lock, the combination with a casing and a bolt supported therein, of a permutation bar controlling the movements of the bolt, longitudinally movable bars arranged to act on and move the permutation bar when they are operated in proper sequence, the said longitudinally movable bars being also rotatively supported and constructed so that each will act on the permutation bar only when turned to a certain angular position.

15. The combination stated in claim 14, having the bars that move the permutation bar formed with non-circular portions and supports for the bars fitting the non-circular portions, thus preventing their rotation, other portions of the bars being constructed to permit the bars to be angularly adjusted when moved to certain longitudinal positions.

FRANK E. WILLIAMSON.
